UNITED STATES PATENT OFFICE.

JOHN W. GRAHAM, OF HINTON, WEST VIRGINIA.

TYPGRAPHICAL OR SLUG-CASTING MACHINE.

1,298,492.

Specification of Letters Patent. Patented Mar. 25, 1919.

Application filed May 8, 1915, Serial No. 26,780. Renewed February 18, 1919. Serial No. 277,817.

To all whom it may concern:

Be it known that I, JOHN W. GRAHAM, a citizen of the United States, residing at Hinton, in the county of Summers and State 5 of West Virginia, have invented certain new and useful Improvements in Typographical or Slug-Casting Machines, of which the following is a specification.

My invention relates to typographical or 10 slug casting machines, such as linotypes of the original construction, wherein circulating matrices are released from a magazine in the order in which their characters are to appear in print, and then assembled in line, 15 together with expanding spacers, the composed line brought in contact with the face of a mold, the mold filled with molten metal to form a line of type or slug against the matrices, which produce the type characters 20 thereon, and the matrices thereafter returned to the magazine from which they were originally drawn.

More particularly it relates to that class 25 of machines, having a series of magazines, any one of which can be shifted into operative position, and wherein each magazine is removable and interchangeable.

In the drawings of my invention, I have shown it applied to a linotype machine, but 30 it will be apparent that it may be applied to other machines, such as typesetting, and typecasting machines, and many changes and variations made therein, without departing from the spirit or principle of this 35 invention.

Referring to the drawings, Figure 1 is a side view of a portion of a linotype machine having my invention applied thereto. Fig. 2 is a front view of the forked arm A, showing 40 part of the raising and lowering mechanism. Fig. 3 is a side view of a section of a magazine showing the escapement mechanism. Figs. 4 and 5 show the locking pin. Fig. 6 shows a top view of a magazine resting in its rack or basket. Fig. 7 is a side view of Fig. 6. Fig. 8 is a perspective view 45 of a section of a magazine resting in its rack or basket.

Referring to Fig. 1—

50 A represents the main frame having a vertical member and an upper transverse member, the latter of which carries a pivot

near its end upon which a basket is swung, and continued forward to support the frame A¹.

A¹ represents a frame which houses the shaft A³, and also the screws used in raising and lowering the basket. This frame A¹ is pivoted to the main arm A on both sides, by the pins A².

A³ shows a shaft to operate the screws D.

A⁴ shows an arm extended out from the main arm A, to house the locking device and to act as a guide for the basket.

A⁵ shows the locking device.

A⁶ shows the holes in the strap B², in which the lock pin A⁵ fits, to lock the magazines.

B is the complete basket, consisting of the several individual baskets.

B¹ shows the casting to which the basket is affixed, and which is pivoted to the arm A at the pivot T.

B² shows the straps that form the ends of the basket.

B³ shows the angle iron sides of the individual baskets.

C shows the shaft which houses part of the power raising and lowering mechanism.

D shows the screws to raise and lower the basket.

G shows a magazine.

H shows the rods connecting the locking device with the entrance and escapement channels.

L shows the lever to operate the power raising and lowering device.

N shows the hand wheel to operate the hand raising and lowering device.

Y¹ shows the entrance channel.

Referring to Fig. 2—

C¹ shows two pulleys which run loose on the shaft C, and so affixed by any desired means, that they cannot move endwise on the shaft, and so bored out as to receive the 95 tapered ends of the friction cone C⁴.

C² shows a straight belt connecting one pair of the pulleys C¹ and E.

C³ shows a twist belt connecting the other pair of the pulleys C¹ and E.

C⁴ is a friction cone splined on the shaft C.

C⁶ shows a slot in the cone C⁴ to receive the forked end of the lever L.

E shows two pulleys on the shaft A³.

P shows a bevel gear on the shaft N¹.

P¹ shows a bevel gear made fast to the loose pulley C¹.

N shows a hand wheel to operate hand 5 raising and lowering device.

S shows a coil spring which throws the gear P out of mesh with the gear P¹, when not in use.

Referring to Fig. 3—

10 K shows a key rod.

K¹ shows a trip finger attached to a key rod.

V shows a verge.

15 V¹ and V² show the pins between which the verge is pivoted.

V⁴ shows a spring to hold the verge in place.

X shows the matrices.

Y shows the escapement channel.

20 Referring to Fig. 8—

G shows a magazine.

G¹ shows the projected end of the strengthening bar.

25 G² shows the dog which holds the magazine in place, working in conjunction with G¹.

J shows the sheet iron lining in the basket.

In operating the machine, to raise and lower the basket, the lever L, whose forked 30 end fits into the slot C⁶ of the cone C⁴, and which is pivoted on the pin C⁷, is moved so as to bring the cone C⁴ in contact with one or other of the clutch pulleys C¹. Both of the pulleys C¹ are connected to the pulleys 35 E on the shaft A³, one by a cross or twist belt, the other by a straight belt; thus they operate the shaft A³, each in opposite directions. The shaft A³ housed on the frame A¹, is fitted with bevel cog gears, which 40 intermesh with bevel cog gears on the screws D, to raise or lower the basket.

To unlock the magazines the lever A⁶ is moved forward or toward the front of the machine, this turns the pin A⁵, (shown in Fig. 4) and in turning, the pin withdraws 45 from the socket in which it rests and thereby unlocks the magazine. The lock pin is held in place by any desired means. When the lock pin A⁵ is turned to unlock the magazines, it also opens the channel entrance outward, and also the escapement channel by means of connecting rods H and the key rods and trip fingers, which are attached to the supporting frame work of the channel Y.

50 To remove a magazine from its basket, the magazine is moved back a sufficient distance to disengage the projections G¹, from the dog G², then the magazine is raised up to allow the projection G¹ to pass over the dog G² and the magazine is removed from the front of the machine. To place the magazine in the basket this operation is reversed.

In the drawings I have shown my invention in a preferred way, but it is obvious that 65 many changes and variations may be made

therein, without departing from the spirit or principle of the invention.

Having described my invention, its construction and operation, what I claim and desire to secure by Letters Patent of the 70 United States, is as follows:

1. In a typographical machine, in combination, a frame having a pivot, a plurality of removable magazines, a basket hinged to said pivot made to house said magazines in 75 such position that their rear ends are closer together than their front ends, a pair of stationary entrance and exit channels relatively remote from and on the same side of said pivot, but in substantial alinement therewith and between which the basket and magazines are adapted to swing about said pivot whereby the magazines are successively brought into alinement with said common entrance and exit channels as desired. 80

85 2. In a typographical machine the combination of a plurality of removable magazines, a basket made to house the said magazines, so that they are closer together at their rear ends than at their frontal ends, a pivot to which the basket is hinged; a forked arm made with a projection backward to house said pivot at a point in alinement with the entrance and escapement channels, and a supporting frame pivoted to the frontal extension of the forked arm, and housing a screw mechanism to raise and lower the basket, and such screw mechanism, and its supporting frame, placed over and above the basket, which it is designed to raise and lower. 90

95 3. In a typographical machine, the combination of a basket to house a plurality of magazines, and so made that the frontal ends of the said magazines are farther apart than the rear ends, a pivot upon which the basket is hinged, a screw mechanism to raise and lower the basket; a frame made pivoted to the forked arm to house the said screw mechanism, said forked arm made with forward and backward projections, to house the pivot and the screw mechanism, a power raising and lowering device to raise and lower the basket, and the center being in alinement with the entrance and escapement channels 100 so that the magazines will come into operative position at both their ends at the same time, without any devices or mechanisms being added to the ordinary entrance channel or escapement channel. 105

110 4. In a typographical machine, the combination of a plurality of removable magazines, a basket to house the magazines, so that their frontal ends are farther apart than their rear ends, a pivot upon which the basket is hinged, a screw mechanism for raising and lowering the basket, a frame to house and support the screw mechanism, a forked arm to house the pivot, and supporting frame 115 of the screw mechanism, a power raising and 120

125

lowering device, consisting of normally idle pulleys and belts, and a moving friction cone, and means to engage the moving friction cone with the idle pulleys, and means to 5 transmit the motion to the screw mechanism to raise and lower the basket.

5. In a typographical machine, the combination of a plurality of removable magazines, strengthening bars associated with each 10 magazine, a basket to house the magazines, and so constructed that the individual baskets are set farther apart at their frontal ends, than at their rear ends, dogs affixed to the inside of the basket to engage the projecting ends of the strengthening bars of the 15 magazines, and so shaped as to hold the magazines in position, both horizontally and vertically, a locking device to lock the magazines in operative position, a lever to operate 20 the locking device, links to move the channel entrance and escapement channel toward and away from the ends of the magazines, and means whereby the locking mechanism, the channel entrance, and the escapement 25 channel are all controlled by a single operative lever.

6. In a typographical machine, in combination, a frame having a vertical member and an upper transverse member, a pivot 30 near one end of said transverse member, a basket suspended therefrom, a plurality of removable magazines radially disposed within said basket with respect to said pivot, a pair of entrance and exit channels in alignment with each other and said pivot, one of 35 which is supported from said vertical member, and means for moving said basket in the arc of a circle about the pivot between the entrance and exit channels.

40 7. In a typographical machine the combination of a plurality of removable magazines, a rack to house said magazines so that they are closer at their rear than at their frontal ends, means to shift said rack, a 45 forked arm having forward and backward projections, a pivot on which said rack is supported from said backward projections, and a support pivoted to the forward projections of said forked arm connected with 50 said rack.

8. In a typographical machine the combination of a plurality of removable magazines, a rack to house said magazines on an arc whereby they are closer at their rear 55 than at their frontal ends, means to shift said rack, a forked arm having forward and backward projections, a pivot on which said rack is supported from said backward projections, a supporting frame pivoted to the 60 forward projections of said forked arm and connected with said rack including a screw mechanism to raise and lower said rack, said screw mechanism being supported at a point over and above said rack which it is 65 designed to raise and lower.

9. In a typographical machine the combination of a plurality of removable magazines, a rack to house said magazines with their rear closer than their frontal ends, means to shift the said rack, a forked arm 70 having forward and backward projections, a pivot on which said rack is supported by said backward projections, a supporting frame pivoted to the forward projections of said forked arm including a mechanism to 75 raise and lower the said rack, said frame having supported at a point over and above said rack which it is designed to raise and lower, a shaft having two normally idle friction pulleys thereon, a normally moving 80 friction cone splined to said shaft, and means to engage the said friction cone with either one of said pulleys.

10. In a typographical machine the combination of a plurality of removable magazines, a rack to house said magazines with their rear ends closer than their frontal ends, means to shift the said rack, a forked arm having forward and backward projections, said rack being pivoted to said backward 90 projections, a supporting frame pivoted to the forward projections of said forked arm, a mechanism to raise and lower the said rack, supported at a point above said rack which it is designed to raise and lower, a 95 shaft having two normally idle friction pulleys, a normally moving friction cone splined to said shaft, means to engage the said friction cone with either of said pulleys, and means to transmit the motion to said 100 mechanism to shift said rack in either direction as desired.

11. In a typographical machine, the combination of a plurality of removable magazines, a rack to house said magazines, means 105 to shift said rack, a forked arm having forward and backward projections, said rack being pivoted to said backward projections, a supporting frame pivoted to the forward projections of said forked arm, a screw 110 mechanism to raise and lower said rack, supported at a point over said rack which it is designed to raise and lower, a shaft having on it two normally idle friction pulleys, a normally moving friction cone 115 splined to the said shaft, means to engage said friction cone with either one of the said pulleys, means to transmit the motion to the said screw mechanism to shift the said rack in either direction as desired, lock pins to 120 lock said magazines, having elongated heads on the said pins, a lever to operate the said lock pins, rods connecting the entrance and escapement channels with opposite ends of the said elongated heads of the lock pins, 125 and means whereby the locking and unlocking of the magazines and the moving of the entrance and escapement channels into and out of operative position are all controlled simultaneously by one operation. 130

12. A typographical machine having a plurality of matrix magazines and supporting means therefor, including extensions disposed rearwardly from the distributor head, and frame members pivotally supported on said extensions for movably supporting said magazines in the machine, said magazines being disposed in planes converging at the axis of said frame members.
- 10 13. A typographical machine comprising a frame extended at the rear, distributing means for the matrices depending from said frame; magazine supporting members piv-

otally held on said frame at the rear of said distributing means, and a plurality of matrix magazines slidably held on said supporting means in planes converging at the axis thereof and capable of movement for effecting the selective placement of said magazines, into operative position. 15 20

In testimony whereof I affix my signature in presence of two witnesses:

JOHN W. GRAHAM.
